INVENTOR,

Frank V. Burrow

A. Martell
ATTORNEY.

UNITED STATES PATENT OFFICE.

FRANK V. BURROW, OF LOS ANGELES, CALIFORNIA.

AMUSEMENT DEVICE.

Application filed August 26, 1924. Serial No. 734,204.

To all whom it may concern:

Be it known that I, FRANK V. BURROW, a subject of Great Britain, residing at Los Angeles, in the county of Los Angeles and State of California, have invented new and useful Improvements in Amusement Devices, of which the following is a specification.

My invention relates to amusement devices and more particularly to an amusement device of the merry-go-round type, adapted for carrying passengers in a circular path about a fixed center.

The main object of my invention is to provide an amusement device which is especially adapted for use at amusement resorts and in which persons of all ages may ride in safety and with comfort.

Another object is to provide a device of the character described which by producing a combined circular and vertical motion to passengers riding therein will give them an unusual sensation, while presenting an amusing appearance.

Other objects and advantages will appear hereinafter and while I show herewith and will describe a preferred form of construction, I desire to be understood that I do not limit my invention to such preferred form, but that various changes and adaptations may be made therein without departing from the spirit of my invention as herein-after claimed.

Referring to the drawings which accompany this specification and form a part thereof:

Fig. 1 is a plan view of a portion of my amusement device illustrating its general form and construction.

Fig. 2 is a sectional view of same taken on line 2-2 of Fig. 1.

Fig. 3 is a fragmentary view partly in section and partly in elevation of the track with cars thereon, illustrating their positions with relation to each other, the view being taken on line 3-3 of Fig. 1.

Fig. 4 is an enlarged plan view of one of the cars.

Fig. 5 is a rear view of same.

In general the device consists of an endless series of connected cars 10, running on a circular track in the form of two concentric rails 11 and 12, the series being driven by radial arms 13 regularly spaced and having their outer ends pivotally connected

to the under side of cars at regular points in the series and their inner ends pivotally connected to a common drive wheel 14, which is keyed to a vertical shaft 15 having a gear wheel 16 keyed thereon which meshes with a gear wheel 17 fixed on a drive shaft 18, said drive shaft being driven by a motor not shown. A circular platform 19 surrounds the track and steps 20 lead up to the platform.

The rails 11 and 12 which form the circular track have alternate upward and downward bends 21 and 22 respectively at intervals whose horizontal distance is equal to the length of one of the cars. The wavelength of the resulting wave formed track is therefore equal to the length of two cars.

The cars are preferably made with but two wheels 23 turning on an axle 24 fixed under the car body 25 near the rear end thereof. The front end of each car is provided with a long vertical bearing 26 fixed thereto and the rear end is equipped with a vertical rod 27 extending between brackets 28 and 29 fixed to the top and bottom respectively of the rear part of the car body. The length of the rod exceeds the length of the bearing by twice the vertical distance from trough to crest of the truck waves. The front bearing of each car is adapted to engage with the rear rod of the car ahead so that there is a vertically reciprocating movement of one upon the other when the cars, so connected in an endless series, travel around the tracks. A seat 30 is fixed in the rear end of each car.

The driving arms 13 have bearings 31 on their inner ends which engage with pin sections 32 of drive wheel 14, and bearings 33 on their outer ends which engage with bolts 34 extending through the axle 24 into a bracket 35 fixed under the body of these cars which are in position for connection with the driving arms. The pivots thus formed, having horizontal axes, permit of free vertical movement of the outer ends of the driving arms as the cars to which they are attached rise and fall in their course around the track.

The height of the circular platform 19, with reference to the track, is so fixed that the downward step into a car in its lowest position is equal to the upward step into a car in its highest position. For convenience, in entering and leaving the cars, the bodies

thereof are made with side openings 36 on the side adjacent the circular platform.

The device is operated by applying power to shaft 18 so as to drive the cars around the track in the direction indicated by the arrow in Fig. 1. The driving arms drive the cars to which they are attached and the intermediate cars, connected as they are, must follow. The length of the cars, measured from the center of bearings 26 to the center of rods 27, being equal to the horizontal distance between trough and crest of the track wave, adjacent cars at any instant are either in a highest and a lowest position, or are traveling in opposite vertical directions, while alternate cars are all in the same relative position on the track and are all moving in the same vertical direction. The weight of the car is carried by the axle and wheels and the car is maintained in a horizontal position on the wheels by the front bearing and rear rod connections of the car with the rear rods and front bearings respectively of the adjacent front and rear cars of the series.

Having thus illustrated and described my invention, I claim:

1. An amusement device comprising a circular track consisting of a pair of concentric rails having alternate upward and downward bends to simulate waves, an endless series of connected cars adapted to travel on said track, each of said cars corresponding in length to the semi-wave lengths of said track, slidable connecting means between adjacent cars of said series which maintain all

of said cars in a horizontal position, a plurality of driving arms having their outer ends pivotally connected to occasional cars in said series and their inner ends pivotally connected to a common drive wheel, a vertical shaft to which said drive wheel is keyed, means for operatively connecting said vertical shaft with a motor so that it is rotated thereby, and a circular platform surrounding said track for use when entering or leaving said cars.

2. An amusement device comprising a circular track consisting of a pair of concentric rails having alternate upward and downward bends to simulate waves, an endless series of two-wheeled cars adapted to travel on said track, vertically slideable connecting means in the form of rods and bearings attached to the rear and front ends respectively of said cars, said slideable connecting means being adapted to permit of vertical movement between adjacent cars of said series with relation to each other and simultaneously to maintain all the cars of said series in a horizontal position, a plurality of driving arms having their outer ends pivotally connected to occasional cars of said series and their inner ends pivotally connected to a common drive wheel in the center of said track, operative means for connecting said drive wheel to a motor, so that it is rotated thereby, and a circular platform surrounding said track for use when entering or leaving said cars.

FRANK V. BURROW.
